BOWLING LANE MASKING UNIT

Henry Dreyfuss, South Pasadena, Calif., assignor to
American Machine & Foundry Company, a cor-
poration of New Jersey

Filed Oct. 17, 1966, Ser. No. 4,308

Term of patent 14 years

(Cl. D34—5)

FIG. 1

FIG. 2

FIGURE 1 is a perspective view of a bowling lane masking unit taken from the front thereof, the broken lines indicating a portion of a bowling alley are for illustrative purposes only, and

FIGURE 2 is a top view of the bowling lane masking unit shown in FIGURE 1.

I claim:

The ornamental design for a bowling lane masking unit, as shown and described.
